UNITED STATES PATENT OFFICE.

GUSTAVUS A. ANDEREGG, OF OAK PARK, ILLINOIS, ASSIGNOR TO WESTERN ELECTRIC COMPANY, OF NEW YORK, N. Y., A CORPORATION OF ILLINOIS.

TWISTING-MACHINE.

1,108,312.

Specification of Letters Patent. Patented Aug. 25, 1914.

Application filed September 18, 1913. Serial No. 790,427.

To all whom it may concern:

Be it known that I, GUSTAVUS A. ANDEREGG, a citizen of the United States, residing at Oak Park, in the county of Cook and State of Illinois, have invented a certain new and useful Improvement in Twisting-Machines, of which the following is a full, clear, concise, and exact description.

This invention relates to twisting machines, and more particularly to machines for the twisting of conductors for use in electric cables and like articles of manufacture.

The object of this invention is to provide a machine for twisting conductors in such a manner that the twisted conductors are of the same length, whereby the electrical qualities of said twisted conductors are greatly improved when said conductors are used in electric cables.

The features of this invention are the means provided for equalizing the speed at which the conductors travel through the twisting machine and other details of structure and combination of parts as will hereinafter more clearly appear.

This invention is illustrated in the accompanying drawing in which the same reference characters are used throughout to designate the same parts, and in which—

Figure 1 is a front elevation of a twisting machine embodying this invention, and Fig. 2 is a view on lines 2—2 of Fig. 1.

Referring to the drawing, 5 and 6 are side frame members joined at top and bottom respectively by supporting plates 7 and 8. Mounted upon the bottom supporting plate 8 is a revolving frame comprising a shaft 9 carrying a bar 10 upon each end of which is mounted a yoke 11. Mounted upon the upper end of the shaft 9 and hollow hubs 12, 12 of the yokes 11, 11 is an auxiliary inverted T-shaped frame 13, the upper end thereof being hollow and journaled in the upper supporting plate 7. The housing 14 contains the usual gears for driving a capstan 15 for drawing the conductors through the revolving frame, said gears meshing with a gear on the upper end of the frame 13. Since the arrangement of the gears for driving the capstan from the frame 13 is well known, it is not considered necessary to either show or describe them. The revolving frame is driven through the neces-

sary shafting and gears from a suitable motor—such as is shown at 20 in Fig. 1.

In order that the twisted conductors may be properly wound on a receiving reel, there are provided pedestals 21 and 22 in which is journaled a shaft 23 which carries a reel 24 and is driven by means of a belt 26 passing over a pulley 25 carried by said shaft and over a pulley 27 carried by a shaft 28 between the motor 20 and the revolving frame.

To provide for the proper distribution of the twisted conductors on the receiving reel, a distributor screw 29 is journaled in the upper ends of the pedestals 21 and 22. The distributor screw 29 carries a distributor block 30 which guides the twisted conductors, and is driven by means of a belt 31 passing over pulleys 32 and 33 carried by the shaft 23 and the distributor screw 29, respectively.

To make the two conductors travel at the same rate of speed through the twisting machine, the vertical portion of the auxiliary inverted T-shaped frame is formed into two legs 40 and 41 (Fig. 2) joined at top and bottom. Each of the legs 40 and 41 is provided with horizontal extending arms 42 and 43 carrying at their outer ends short shafts 46, 46 upon which are mounted flat rimmed wheels 44, 44. These wheels 44, 44 have flanges 45, 45 formed on each edge of the periphery thereof.

Referring now to the operation of a twisting machine embodying the invention hereinbefore described and illustrated in the accompanying drawing, the spools containing the conductors to be twisted are mounted in a horizontal position in the yokes 11, 11, as shown in Fig. 1. The conductor 48 from the spool mounted in the yoke 11 at the left of the machine is led up through the hollow hub 12 thereof, up and over the left-hand wheel 44, down, under and then over the right-hand wheel 44, down and under the left-hand wheel 44 (this cycle may be repeated two or three times), then passing from the left-hand wheel 44 into the hollow end of the vertical portion of the auxiliary inverted T-shaped frame 13, and here is joined by the other conductor 49 which has followed a similar course from the right-hand reel. The two conductors 48 and 49 now pass through the hollow end of the vertical portion of the auxiliary inverted T-

shaped frame 13 where they are twisted together due to rotation of the revolving frame and the forward movement of the conductors, around the capstan 15 several times 5 and finally onto the receiving reel 24. When the machine is started, the revolving frame, wheels 44, 44, capstan 15 and receiving reel 24 begin to revolve, the wheels 44, 44 being driven by the conductors which pass around 10 their peripheries. The action of each conductor in passing around each of the wheels 44, 44 causes the equalization of the speed of the conductors through the mechanism.

Among the advantages of this invention 15 are ease with which the few and simple parts may be assembled; no parts need be changed when different sizes of conductors are to be twisted; and the parts are so arranged that the minimum amount of time 20 is required for threading up the machine ready for operation.

While this invention has been described as applied to a machine for twisting conductors for use in electric cables, it will be 25 readily apparent that it is applicable to the twisting of wires, strands and all other similar materials where it is desired that said wires, strands and so forth shall be fed at the same rate of speed through said machine, and this invention is therefore not limited to the particular application herein 30 described.

I claim:

1. In a twisting machine, a plurality of 35 independently revolvable means each traversed and driven by each of the conductors to be twisted for equalizing the speed thereof.

2. In a twisting machine, a revolving

frame, a plurality of spool supports carried 40 thereby, means for drawing off the twisted conductors, and independently revolvable wheels around each of a plurality of which each conductor to be twisted passes.

3. In a machine of the character de- 45 scribed, mechanism for twisting a plurality of conductors, means for drawing the conductors through said mechanism, and a plurality of drums around the periphery of each of which each of the conductors is 50 passed for equalizing the speed thereof through said mechanism.

4. In a machine of the character de- 55 scribed, a revolving frame for twisting a plurality of conductors, means for drawing the conductors through said frame, and a plurality of flat rimmed wheels around the periphery of each of which each of the conductors is 60 passed for equalizing the speed thereof.

5. In a machine of the character de- 65 scribed, a revolving frame for twisting a plurality of conductors, means for drawing the conductors through said frame, and means for equalizing the speed of the conductors comprising an auxiliary frame mounted upon said revolving frame and two wheels mounted in said auxiliary frame each of which is traversed by each of the conductors. 70

In witness whereof, I hereunto subscribe my name this 4th day of September, A. D. 1913.

GUSTAVUS A. ANDEREGG.
